UNITED STATES PATENT OFFICE.

RALPH SWITZER MOORE, OF EL PASO, TEXAS, ASSIGNOR TO AMERICAN SMELTING AND REFINING COMPANY, OF NEW YORK, N. Y., A CORPORATION OF NEW JERSEY.

METHOD OF PROTECTING FURNACE BRICKWORK.

No Drawing.

Application filed September 8, 1927. Serial No. 218,370.

This invention relates to a method of protecting furnace brick work from the erosive action of combustible materials.

It has been found that furnace charges combine chemically with adjacent surfaces such as a brick furnace lining and cause disintegration thereof. Should a silicious brick lining be employed and a basic charge burned in the furnace, the fine particles of dust set free by the charge dropping into the furnace coming in contact with the lining will set up a chemical or fluxing action which results in the wearing away or erosion of the material. Difficulty may also be experienced by reason 10 of the charge being too readily fusible whereby a portion of said dust may become fused upon contact with the sides and roof of the furnace. This fused material is then capable of exerting a stronger chemical action upon 15 the exposed surfaces than would be the case were it maintained in solid form.

This invention provides for the protection of furnace linings by the addition of a neutralizing material blown into the furnace as 20 dust when the charge is dropped whereby the dust from the charge coming in contact with said lining will be prevented from reacting chemically therewith. The nature and amount of the material added will depend 25 upon the specific type of charge and lining employed in each particular case.

Although the novel features which are believed to be characteristic of this invention will be particularly pointed out in the claims 30 appended hereto, the invention itself, as to its objects and advantages, the mode of its operation and the manner of its organization may be better understood by referring to the following description in which a particular commercial embodiment thereof is disclosed. It 35 will be understood however, that the processes and the steps thereof may be modified in various respects without departing from the broad spirit and scope of the invention.

In the following description and in the claims the various steps in the process and the details comprising the invention will be identified by specific names for convenience but they are intended to be as generic in their 40 application as the art will permit.

As a specific example, the process in accordance with the present invention may be applied to a reverberatory furnace having a silicious brick lining. In the case of the usual basic charge, fine dust particles from the dropping charge coming in contact with the lining will exert a chemical or fluxing action thereon with the consequent erosion or wearing away of the surface particles. It 55 has been found in practice that the lining must be renewed after a given number of charges in order to replace the material which has been lost by reason of the above mentioned action.

In accordance with the present invention, 60 a neutralizing material preferably in a finely ground form is blown into the furnace as dust, preferably at the time of inserting the charge 65 therein. This material should be of such nature that the chemical action ordinarily produced by the charge is neutralized thereby. For example, a silicious material comprising aluminous clay, mill tailings or other 70 suitable substances has been found satisfactory.

By neutralizing the dust from the basic charge of a reverberatory furnace having a silicious lining by using an excess of the neutralizing material, it has been found that the furnace brick work may be built up and caused to increase in thickness. The quantity of neutralizing material may, however, be suitably determined to maintain the thickness of the lining constant and prevent either 75 building up or wearing away thereof. Obviously, the necessity of renewals will thereby be largely eliminated.

In the case of coal-firing of reverberatory furnaces or boilers, the ash has been found to attack the refractory lining due to the fusibility thereof. In accordance with the present process, a suitable quantity of neutralizing material such as silica or alumina may be fed into the furnace in conjunction with the coal to raise the fusion point of the mixture above the temperature of the furnace and prevent the ash from reacting with the lining or forming slag in the ash pit. It has been found that a coal with a silicious ash 80 may actually build up the lining whereas it 85

had been rapidly eroded when a coal having a low fusible ash had been used.

Various means may be employed for injecting a neutralizing material into the furnace since it may be pre-mixed with the charge in suitable proportions or it may be separately injected at the time of the addition of the charge or at such other times as may be found necessary to maintain the atmosphere in contact with the lining in neutral condition.

It has been found convenient and satisfactory in reverberatory furnace operation to inject a quantity of finely powdered silicious dust into the combustion chamber simultaneously with the usual basic charge. Such a procedure has been found to produce the above mentioned desirable result and to permit a ready control by varying the amount of neutralization material added and the time of addition to suit the requirements of a particular case. The proper proportions may be readily determined by observing the surface of the brick work as the combustion progresses and noting from time to time the condition thereof. It has been found preferable to use an excess of neutralizing material in order to positively prevent erosion of the lining even though a slight building up is produced thereby.

The above mentioned process provides a cheap and practical means for preventing frequent renewals of furnace linings and the consequent expense attached thereto. This results in a substantial saving since, in addition to the cost of lining materials and labor, the furnace must be removed from operation while being repaired thereby increasing the overhead.

40 Although certain novel features of the invention have been shown and described and are pointed out in the annexed claims, it will be understood that various omissions, substitutions and changes in the several steps of the process and in its operation may be made by those skilled in the art without departing from the spirit of the invention.

What is claimed is:

1. The method of protecting furnace brick work from the erosive action of the charge burned therein, which comprises inserting into the furnace a neutralizing material in dust form for preventing the particles of the charge in contact with the brick work from exerting a chemical or fluxing action thereon.

2. The method of protecting furnace brick work from the erosive action of materials burned therein, which comprises injecting into said furnace a neutralizing dust, said dust being capable of combining with the dust of the furnace charge and neutralizing any chemical action between said dust and said brick work.

3. The process of feeding a furnace having

an acid lining with a charge having a basic reaction, which comprises injecting into said furnace an acid dust material in quantities sufficient to neutralize the dust formed in dropping said charge.

4. The process of feeding a basic charge into a furnace having a silicious lining, which comprises injecting into said furnace a quantity of silicious dust material sufficient to neutralize the dust formed by dropping said charge whereby reaction between said charge and said lining is prevented.

5. The process of feeding a reverberatory furnace, having an acid lining, which comprises injecting a quantity of finely divided acid material as dust into the presence of a basic charge whereby chemical reaction between said lining and dust from said charge is prevented.

6. The process of feeding a reverberatory furnace having an acid lining, which comprises injecting a quantity of silicious material as dust into the presence of a basic charge whereby chemical reaction between said lining and dust arising from said charge is prevented.

7. The process of feeding a reverberatory furnace having an acid lining, which comprises injecting a quantity of silica dust into the presence of a basic charge whereby chemical reaction between said lining and dust from said charge is prevented.

8. The process of feeding a reverberatory furnace having a silicious lining, which comprises injecting a quantity of acid material as dust into the presence of a basic charge whereby chemical reaction between said lining and dust from said charge is prevented.

9. The process of operating a combustion chamber having a lining susceptible to attack by the ash of the material burned therein, which comprises introducing into said combustion chamber as dust in the presence of a charge a material capable of preventing said ash from reacting with said lining by raising the fusion point of the mixture above the temperature of the furnace.

10. The process of feeding a combustion chamber having an acid lining, which comprises introducing into said combustion chamber a charge having a basic reaction and neutralizing the dust from said charge with a dust having an acid reaction.

11. The process of feeding a combustion chamber having a silicious lining, which comprises introducing therein a charge having a basic reaction and neutralizing the dust from said charge by the addition of a silicious dust whereby reaction thereof with said lining is prevented.

12. The process of feeding a combustion chamber having a silicious lining, which comprises introducing therein a charge having a basic reaction and neutralizing the dust from

said charge by the addition of a silica dust
whereby reaction thereof with said lining is
prevented.

In testimony whereof I have hereunto set
5 my hand.

RALPH SWITZER MOORE.
